SOLENOID FIRING MECHANISM FOR
MACHINE GUNS

John C. Koonz and La Vern Edward Quinnell,
Fort Wayne, Ind., assignors, by mesne assignments,
to The Magnavox Company, Fort Wayne, Ind., a corporation of Delaware

Application November 27, 1941, Serial No. 420,612

2 Claims. (Cl. 89—28)

This invention relates to machine guns and more particularly to such guns intended for use in tanks.

As is well known, it is desirable that machine guns should be so mounted in a tank that if the tank becomes involved in difficulty and is unable to operate, the gun may be readily removed so as to be usable for operations independently or outside of the tank.

One of the objects of the invention is to provide new and improved means for operating the firing mechanism of a machine gun of the above mentioned type.

A further object of the invention is to provide a firing mechanism operating means, preferably of the direct-acting solenoid type, which will be highly efficient and positive in action.

A still further object of the invention is to provide a solenoid which is much lighter in weight and which will require less electrical energy for its operation than solenoids heretofore utilized for similar purposes.

The invention consists in the novel construction, arrangement and mechanism to be herein-after described and claimed, for carrying out the above stated objects and such other objects as will appear from the following description of the accompanying drawings.

In the drawings:

Figure 1 is a side elevation of a machine gun showing the structure of the present invention in its assembled position.

Figure 2 is a similar view to Figure 1, but with the parts in disconnected position.

Figure 3 is a side elevational view, on a larger scale, of part of the structure shown in Figure 1.

Figure 4 is a perspective view of a bracket utilized by the invention.

Figure 5 is a side elevation of the solenoid assembly according to the present invention.

Figure 6 is an end view of the assembly of Figure 5.

Figure 7 is a plan view thereof.

Figure 8 is a central vertical section through the assembly of Figure 5 on a larger scale.

Referring to the drawings, in Figures 1 and 2 more particularly, we see at 1 the gun casing or body and at 2 the barrel of the gun. The gun casing 1 is provided at opposite sides with a depending lug or bar 4 between which, in the operative position of the gun, is disposed a bracket 6 and there held in place by a pin 8 which is passed through openings 10 in the lugs 4 and through a bore 12 in the bracket 6.

The solenoid may comprise a circular casing 14

(see Fig. 8) which, at its upper end is closed by a plate 16 centrally bored as at 18 to receive the upper end of the core 20 of the solenoid and through which projects the trigger shaft 22, the opposite end of which shaft is housed within the plunger 24. The reference 26 indicates the field coil or coils from which extend to the terminal block 28 the leads 30. To the block 28 is connected the cable 31 which leads to any suitable source of electrical energy (not shown).

The upper plate 16 is provided with an integral extension 32 constituting an intermediary member which, it is to be particularly noted, is disposed at an angle to said plate 16. The bracket 6 is bored at 34 and 36 to receive screws 38 and 40 which are adapted to project respectively into screw-threaded openings 42 and 44, whereby the intermediary member or angularly disposed extension 32 and the bracket 6 are interconnected.

20 To the extension 32 is secured, as by rivets 46 or other suitable fastening means, a casing comprising the side and front plates 48 and 50, whereby to provide in combination with the angularly disposed extension 32, a housing triangular in cross section in which is mounted and thereby protected, the terminal block 28. The front plate 50 of the casing is provided with a bushing 52 which receives and protects the cable 31 and on to which may be attached a flexible conduit 54 to enclose said cable. The front plate 50 may be continued downwardly to form a cap 56 closing the lower end of solenoid casing 14 to which the cap is secured as by rivets 58.

60 is the finger trigger of the gun, while 62 is 35 a tip with which the shaft 22 is provided being secured thereto by a cotter pin 64.

From the above it will be seen that the solenoid is not directly connected to the gun, but instead is indirectly connected thereto through 40 the intermediary member 32 and the bracket 6. With the solenoid so mounted it is to be noted that the tip 62 on the trigger shaft 22 is positioned directly below the finger trigger 60 of the gun.

45 In previous solenoid assemblies the axis of travel of the trigger shaft has not been tangent to the radius through which the finger trigger 60 moves. On the contrary, in the present arrangement, by mounting the solenoid through the medium of the intermediary member 32 and disposing the latter at an angle of 25° or substantially so to the solenoid, the axis of the trigger shaft 22 is placed tangent to the radius of travel of the trigger finger 60. In this way

a given force on the trigger shaft 22 is utilized 100%.

The above in turn leads to another advantage in the present arrangement, i. e., the weight of the solenoid can be considerably reduced as well as the electrical power employed in its operation. For example, the present solenoid need only weigh one pound and use a current drain of 4 amperes at 24 volts, as contrasted with prior structures in which the solenoid has weighed two and three quarters pounds and has required a current of 8 amperes at 24 volts.

Having thus disclosed the invention, we claim:

1. An attachment adapted to be readily connected and disconnected to a machine gun casing for operating the finger trigger thereof, comprising a solenoid, a casing therefor, an end plate secured to one end of said solenoid casing and provided with an extension disposed at an angle to said plate for mounting the solenoid on the 20

gun casing at an angle to the gun casing, a trigger operating shaft mounted in said solenoid and extending through and beyond said end plate and adapted to directly engage the finger trigger tangentially to the radius of the travel of the free end thereof, substantially as and for the purpose set forth.

2. An attachment adapted to be readily connected and disconnected to a machine gun for operating the finger trigger thereof, comprising a solenoid, a casing therefor, an end plate secured to one end of said casing and provided with an extension disposed at an angle to said plate, a triangular housing connected with and interposed between said extension and casing, adapted to house and protect terminals for the solenoid.

JOHN C. KOONZ.
LA VERN EDWARD QUINNELL.
